UNITED STATES PATENT OFFICE.

GEORGE R. WYMAN, OF WALPOLE, MASSACHUSETTS, ASSIGNOR TO BIRD & SON, INCORPORATED, OF WALPOLE, MASSACHUSETTS, A CORPORATION OF MASSACHUSETTS.

SHINGLE AND METHOD OF LAYING THE SAME.

Application filed September 23, 1924. Serial No. 739,392.

This invention relates to an improved form of shingle and to the method of laying the same.

The main object of the invention is to produce a shingle having formed as an integral portion thereof a locking tongue or tab, which, when the shingles are laid, will engage or interlock with the adjacent shingles and thus cause the various shingles forming 10 the roofing or siding to lie flat.

The construction of the shingle is such that no separate securing bars, straps or similar members, have to be fastened to the shingle, but, on the other hand, the tongue or tab 15 is preferably produced as an integral part of the shingle body or as an extension thereof.

Under the method of laying which is employed, there are no exposed nails, but, on 20 the other hand, the nails utilized in part to secure the shingles in place are covered over in the act of placement of the various shingles.

The structure and the manner in which the 25 shingles are laid are illustrated in the annexed drawings, wherein:

Fig. 1 is a plan view of a series of shingles laid up in accordance with my invention;

Fig. 2 a similar view on a larger scale of 30 one of the shingles;

Fig. 3 a perspective view of a portion of a shingle showing the locking tongue turned inwardly beneath the body, or in that position which it occupies when the shingle is 35 laid; and

Figs. 4 and 5, sectional views taken, respectively, on the lines IV-IV and V-V of Fig. 1.

The shingle may be produced from any 40 suitable material, such, for instance, as sheet felt or felt paper, saturated or impregnated with any suitable waterproofing material, the shingle being preferably coated with asphalt, and surfaced with crushed slate, such as the usual slate surfaced ready roofing 45 or shingles, or the like.

The shingle body is preferably polygonal in outline, and in the instant case is shown as rectangular in contour and denoted by 1. 50 Adjacent one corner of the blank the opposite edges as 2 and 3 are notched out as at 4 and 5, the notches being preferably right angled ones and slightly curved or rounded at their base or inner end.

55 There is thus produced a tongue or tab

6, the outer end whereof is pointed and the longitudinal axis of which is coincident with one of the diagonals of the shingle body.

The marginal portions of the body or the upper portions of the notches, designated by 60 7 and 8, adjacent the root of the tongue are in alinement and stand at right angles to the axis of the tongue, so that when the tongue is bent inwardly beneath the body, or conversely, when the body is turned up- 65 wardly over the tongue as in the act of laying the shingles, there will be produced a substantially continuous line across the lower portion of the shingle, as clearly shown in Fig. 1. 70

In actual use, I prefer to bend the tongue inwardly beneath the shingle body at the time of manufacture, this for the reason that the material at such time is relatively 75 soft and there is no tendency to crack or disrupt the structure. It is conceivable, however, that the shingles may be shipped flat, but care must be taken, if this is done, not to lay them in cold weather without softening the shingles slightly before the tongue 80 is bent inwardly, or conversely, the body bent over the tongue.

In laying the shingles a course of shingles, or triangular pieces forming a lower course, in case a finish strip is not employed 85 at the lower edge of the roof or siding, and designated as a, b, and c, are secured to the roof or siding structure at their adjacent corners by nails, as 9 and 10. Such corners are brought close together and the nails so 90 located as to be spaced apart a distance somewhat in excess of the width of the tongue or tab 6. A second row or course of shingles as d, e, f and g, is then positioned, the tongue of each shingle being respectively passed 95 upwardly beneath the adjacent corners of the previously positioned and secured shingles, which corners may be temporarily raised by the introduction of the claw of a hammer or other suitable tool. 100

When the tongue is thus inserted, if the shingle had not been previously bent, the shingle is turned upwardly and is secured in place by nails in the manner previously indicated. The shingle thus positioned overlies and overlaps the edges of the previously laid adjacent shingles and the lower edge thereof is held closely in place by the tongue or tab 6, which is held down by the overlying and inwardly projecting corners of 110

the adjacent shingles of the previously laid series or row.

By reason of the fact that the tongue is relatively narrow, it is only essential to raise the adjacent corners of the two previously laid shingles in order to insert the tongue. In other words, the bodies of the two adjacent shingles, as for instance *e* and *f*, do not have to be raised but only the corners thereof lying between the two fastening nails, as 9 and 10, in order that the tab or tongue may be readily inserted and passed upwardly between the same. Thus the lay of the previously laid shingles *e* and *f* is not disturbed and no appreciable crack or opening is left between the edges of said shingles *e* and *f* and the previously laid shingle or element *b*. These same conditions obtain throughout the entire roof or siding.

20 The shingles thus laid become interlocked and a shadow effect is produced at the lower edge or butt thereof. Moreover, the construction allows for expansion and contraction without disarrangement or bucking of the shingle. Furthermore, there is little opportunity for the wind to raise the shingle,—a point of manifest advantage. As will be appreciated, there are no slits or cuts in the material which start further tears 30 into the body of the shingle, and the rounding of the root of the notches in the production of the tongue materially aids in preventing the tearing of the shingle, both in handling and in the action of the wind thereon.

Again, with the construction disclosed, the shingles may be readily produced, the notches being formed after the blanks have been cut out, or the shingle as a completed 40 article may be died out of the stock.

The shingles may be readily bundled by offsetting the same as they are stacked up to accommodate double thickness where the tongue occurs; such offsetting is of course not necessary if the tongues are not bent during the course of manufacture, which op-

eration, as above noted is, however, the preferred one.

What I claim is:

1. As a new article of manufacture, a flexible composition shingle rectangular in outline and of the same thickness throughout, having at one corner thereof a tongue formed as an integral portion of the body, said tongue having parallel side edges, the bend 50 of the tongue, when said tongue is folded beneath the body, standing in substantial alignment with the butt edge of the shingle 55 extending outwardly to each side of the tongue.

2. As a new article of manufacture, a flexible composition shingle rectangular in outline and of the same thickness throughout, having at one corner thereof a relatively narrow, pointed tongue formed as an integral portion of the body, the line of junction 60 of the tongue with the body portion standing in alignment with the adjacent edges of the shingle to each side thereof, said edges 65 and line of junction forming, when the tongue is turned under the body of the shingle the shingle butt.

3. In a roofing or the like, courses of flexible diagonally laid shingles having their horizontal opposite corners closely adjacent 70 and secured by fasteners penetrating said shingles substantially on their horizontal diagonal edges and close to said corners, each shingle being generally rectangular in outline with a transverse exposed butt edge at 80 the lower corner thereof and each having hinged thereto at the butt end a bent under tongue held down solely by the corners of the adjacent shingles overlying the tongue and having a substantial portion of said tongue 85 extending above the line of the fasteners, the width of said tongue being substantially that of the hinge and materially less than said butt edge.

In testimony whereof I have signed my name to this specification:

GEORGE R. WYMAN.
